UNITED STATES PATENT OFFICE.

REUBEN R. BARROW, OF MARL, ALABAMA.

WRENCH.

SPECIFICATION forming part of Letters Patent No. 586,473, dated July 13, 1897.

Application filed July 23, 1896. Serial No. 600,214. (No model.)

To all whom it may concern:

Be it known that I, REUBEN R. BARROW, a citizen of the United States, residing at Marl, in the county of Geneva and State of Alabama,

5 have invented certain new and useful Improvements in Wrenches; and I do hereby declare the following to be a full, clear, and exact description of the invention, such as will enable others skilled in the art to which 10 it appertains to make and use the same.

This invention relates to certain new and useful improvements in wrenches; and it has for its object, among others, to provide a simple and cheap construction of wrench composed of few parts, those readily assembled and most efficient in their operation. The holding device is mounted in a chamber or socket in the movable jaw. The fixed jaw is provided with a hole serving as a bur-set on 15 belt-rivets and the concavity opposite thereto for braiding belt-rivets. The end of the shank is formed to constitute a screw-driver.

Other objects and advantages of the invention will hereinafter appear, and the novel 20 features thereof will be particularly pointed out in the appended claim.

The invention is clearly illustrated in the accompanying drawings, which, with the letters of reference marked thereon, form a part 25 of this specification, and in which—

Figure 1 is a central longitudinal section through my improved wrench. Fig. 2 is a transverse section through the movable jaw. Fig. 3 is a transverse section through the 30 fixed jaw.

Like letters of reference indicate like parts in the several views.

Referring now to the details of the drawings by letter, A designates the shank, at one 35 end of which is the fixed jaw, which may be of any suitable form, provided with an opening b, serving as a bur-set on belt-rivets or other uses, and a concavity b' for braiding belt-rivets or for other uses. The other end of the shank is formed to constitute a screw-driver C, and upon this end is a handle D, of

any suitable form and material, beyond which the screw-driver portion projects. The shank is screw-threaded upon one side, as seen at A'.

E is a movable jaw sleeved upon the shank and having at one side teeth e, adapted to engage those of the shank, while upon the opposite side this movable jaw is formed with a chamber or recess F, in which is pivotally 55 mounted, as at g, the eccentric G, having a handle portion G', extending through the opening in the jaw.

The operation will be apparent. When the handle of the eccentric is thrown out or away 60 from the shank, the eccentric is disengaged from the shank and the jaw free to be moved in either direction thereupon. When adjusted to its desired position, the handle of the eccentric is forced toward the shank, when 65 the eccentric will engage the shank within the bore of the movable jaw and bind the latter securely in position. When the eccentric is disengaged from the shank, the movable jaw has sufficient play upon the shank laterally to disengage its teeth from those of the shank and permit ready movement of the 70 movable jaw.

Modifications in details may be resorted to without departing from the spirit of the invention or sacrificing any of its advantages.

Having thus described the invention, what is claimed as new is—

In a wrench of the character described, a shank, a fixed jaw at one end thereof, said 80 jaw being provided with an opening at right angles to the length of the shank, and with a concavity adjacent to said opening and in the same end of the jaw, substantially as and for the purpose specified.

In testimony whereof I have signed this specification in the presence of two subscribing witnesses.

REUBEN R. BARROW.
